BRICK CUTTING TOOL

Daniel J. Coffey, Bronx, N. Y.

Application January 17, 1947, Serial No. 722,546

6 Claims. (Cl. 125—40)

1

This invention relates to brick cutting tools. It is an object of the present invention to provide a brick cutting tool with a measuring device thereon adapted to be rested over the top of the brick and to act automatically as an engaging element is made to engage to the end of the brick, to measure off the desired amount of brick which is to be cut from the full brick.

It is another object of the present invention to provide a measuring device for a brick cutting tool which can be readily freed once the measurement has been made so that the cutting tool can be raised at an angle without interference to effect an undercutting of the brick when the severance of the same is effected.

It is still another object of the present invention to simplify the procedure of effecting the measurements upon the brick whereby the workman can without separate operations having to first measure off a distance on a brick and mark the same, apply the device readily with one hand while retaining a striking hammer in the other hand and whereby to reduce the number of operations in cutting a brick and wherein the cutting of the brick can be done with safety.

For other objects and for a better understanding of the invention, reference may be had to the following detailed description taken in connection with the accompanying drawing, in which:

Fig. 1 is a side elevational view of the cutting and measuring tool disposed in place upon a brick in preparation for the cutting of the brick, tile or the like.

Fig. 2 is a similar side elevational view with the cutting tool having been tilted and the measuring portion having been raised therefrom in preparation for the effecting of a striking operation upon the cutting tool.

Fig. 3 is a fragmentary top plan view of the measuring stick portion and of the slide thereon.

Fig. 4 is a fragmentary view of the slide with its top portion broken away to show the hinged engaging plate on its bottom side which carries the engaging element which contacts the end of the brick.

Referring now to the figures, 10 represents a building brick adapted to be cut. When this operation is to be effected, a cutting chisel or tool 11 having a sharp cutting edge 12 is placed on the top of the brick. Thereafter the chisel is struck and the end of the brick is knocked off. Inasmuch as it is desirable to have the piece to be put into the wall to have an undercut end, the chisel is tilted as shown in Fig. 2 and retained in this position as the cut is made.

2

Heretofore to measure off the amount of the brick to be cut, the workman first has to find a ruler and a pencil in order to measure and mark the brick and after he has found the same he may have to get down upon his knees upon a board or scaffold to effect the measuring of the brick and thereafter to effect the cutting of the same. According to the present invention the measuring means is provided on the tool and carried with the same and is used with little more effort than when applying the chisel directly to the brick. One face of the chisel 11 is grooved as indicated at 13 to receive an upturned portion 14 of a measuring member 15. This upturned portion 14 will engage with the sides of the groove and prevent any lateral displacement of the measuring member 15 relative to the chisel. This portion 14 is secured within the groove and to the chisel by the disposal of a screw 16 through a slot 17 in the portion 14 and into a threaded hole 18 on the cutting tool 11.

The opposite edges of the measuring member are provided with indentations 19 and 20. These indentations are preferably staggered as between the opposite sides of the member. This is so that a more accurate measurement can be effected. Adapted to be moved upon the notched portion of the measuring member 15 is a slide 21 having depending side portions 22 with openings 23 in the same through which can be extended portions 24 of clamping fingers 25 which are pivotally retained beneath the slide by pins 25' and on the top of the member 15 and these fingers have handle portions 26 which can be pinched or brought together against the action of a hair pin spring 27. The spring 27 normally tends to maintain the projections 24 in the notches 23 and in engagement with the notches 19 and 20 of the measuring portion 15.

To the bottom of the slide, there is hinged as indicated at 21' a member on plate 28 having an adjustable contact 29 adapted to engage the end of the brick to temporarily locate the chisel edge 12 at the preselected distance set off on the measuring member 15. This engaging element 29 is adjustable to have the proper zero setting. It is extended through projections 31 and 32 on the plate and is operated by a wheel formation 33 fixed thereto. A coil spring 34 is fixed within the hinge and will tend to normally keep the plate with the engaging contact 29 in a raised position and against the bottom face of the slide 21.

In the operation of the device, the chisel is placed upon the brick or tile and the measuring portion 15 is drawn over the brick so that the con-

tacting element 29 will engage the end of the brick as shown in Fig. 1. This is done after the adjustment of the slide has been made upon the measuring portion 15 to the proper length of cut to be effected upon the brick. Thereafter, the chisel is tilted, without the contacting element catching and without it leaving brick end face, to the position shown in Fig. 2 and is permitted to do so by virtue of the fact that the contacting element 29 is carried upon a hingeable plate 28. The workman will be able to do this without the contact element 29 rendering any interference to the movement of the chisel. Thereafter the chisel is struck and the brick is severed. The plate 28 is of sufficient width that there is little opportunity for the chisel to be shifted laterally to any great extent.

It should now be apparent that there has been eliminated several of the usual steps which have heretofore been necessary in the cutting of a brick to the proper size. The steps which have been eliminated are the measuring, marking and squaring steps. It is no longer necessary to get down on the knees on a scaffold to measure and mark the brick. A more accurate cutting of the brick is effected whereby to save time and material. The brick which has been cut with this tool makes a more true bond.

While various changes may be made in the detail construction it shall be understood that such changes shall be within the spirit and scope of the present invention as defined by the appended claims.

I claim:

1. A cutting tool for brick, tile and the like having a cutting edge and a portion adapted to be struck with a hammer, a measuring member fixed to one face of the tool and extending rearwardly therefrom, a slide adapted to be adjusted along the measuring member to different distances from the cutting edge of the tool, and an engaging element disposed on the slide adapted to fit over the end of the brick and engage with the end face thereof.

2. A cutting tool for brick, tile and the like having a cutting edge and a portion adapted to be struck with a hammer, a measuring member fixed to one face of the tool and extending rearwardly therefrom, a slide adapted to be adjusted along the measuring member to different distances from the cutting edge of the tool, and an engaging element disposed on the slide adapted to fit over the end of the brick and engage with the end face thereof, and means for hingedly connecting the engaging element to the slide so that the measuring member and the slide may be raised or tilted freely and without disengaging the engaging element from its point of contact with the end of the brick and whereby to permit the cutting tool to have the proper tilt so as to effect an undercutting of the brick piece when severing the same.

3. A cutting tool for brick, tile and the like having a cutting edge and a portion adapted to be struck with a hammer, a measuring member fixed to one face of the tool and extending rearwardly therefrom, a slide adapted to be adjusted along the measuring member to different distances from the cutting edge of the tool, and an

engaging element disposed on the slide adapted to fit over the end of the brick and engage with the end face thereof, said engaging element being adjustable upon the slide to make a zero setting of the same.

4. A cutting tool for brick, tile and the like having a cutting edge and a portion adapted to be struck with a hammer, a measuring member fixed to one face of the tool and extending rearwardly therefrom, a slide adapted to be adjusted along the measuring member to different distances from the cutting edge of the tool, and an engaging element disposed on the slide adapted to fit over the end of the brick and engage with the end face thereof, and means for hingedly connecting the engaging element to the slide so that the measuring member and the slide may be raised or tilted freely and without disengaging the engaging element from its point of contact with the end of the brick and whereby to permit the cutting tool to have the proper tilt so as to effect an undercutting of the brick piece when severing the same, and a spring associated with the hinge connection of the means whereby to normally maintain the plate with the engaging element in a raised position and against the bottom of the slide.

5. A cutting tool for brick, tile and the like having a cutting edge and a portion adapted to be struck with a hammer, a measuring member fixed to one face of the tool and extending rearwardly therefrom, a slide adapted to be adjusted along the measuring member to different distances from the cutting edge of the tool, and an engaging element disposed on the slide adapted to fit over the end of the brick and engage with the end face thereof, said measuring member having notches upon the opposite edges of the same, and catch elements on the slide adapted to engage with the notches to retain the slide in its adjusted position.

6. A cutting tool for brick, tile and the like having a cutting edge and a portion adapted to be struck with a hammer, a measuring member fixed to one face of the tool and extending rearwardly therefrom, a slide adapted to be adjusted along the measuring member to different distances from the cutting edge of the tool, and an engaging element disposed on the slide adapted to fit over the end of the brick and engage with the end face thereof, said measuring member having notches upon the opposite edges of the same, and catch elements on the slide in its adjusted position, and said notches on the opposite edges of the measuring member being respectively staggered with one another so that a closer measurement can be effected.
